Primary Examiner — Susan Bennett Hattan*Assistant Examiner* — Leanne Was-Englehart(74) *Attorney, Agent, or Firm* — Ryan Kromholz & Manion, S.C.(57) **CLAIM**

The ornamental design for a DIN rail for carrying wiring and control products, as shown and described.

DESCRIPTION

FIG. 1 is a perspective view of the DIN rail for carrying wiring and control products;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Double-dashed broken lines illustrate portions of the DIN rail for carrying wiring and control products that form no part of the claimed design, while a single-dashed broken line illustrates a perforation line in the DIN rail for carrying wiring and control products.
